UNITED STATES PATENT OFFICE

AUGUST F. B. STARKE, OF SHELBY, MONTANA

DESIGN FOR A NUTCRACKER

Application filed February 17, 1931. Serial No. 38,694. Term of patent 14 years.

To all whom it may concern:

Be it known that I, AUGUST F. B. STARKE, a citizen of the United States of America, residing at Shelby, in the county of Toole and State of Montana, have invented a new, original, and ornamental Design for Nutcrackers, of which the following is a specification, reference being had to the accompanying drawings, forming a part thereof.

Fig. 2 is a top plan view thereof, a portion being broken away.

I claim:

The ornamental design for a nut cracker as shown.

A. F. B. STARKE.
